DESIGN FOR A MEDALLION OR SIMILAR ARTICLE

Thomas H. Jones, Washington, D. C., assignor to the United States of America, as represented by the Secretary of War

Application January 3, 1947, Serial No. 135,910

Term of patent 14 years

(Cl. D29—19)

To all whom it may concern:

Be it known that I, Thomas H. Jones, a citizen of the United States and resident of the city of Washington, District of Columbia, have invented a new, original, and ornamental Design for a Medallion or Similar Article, of which the following is a specification, reference being had to the accompanying drawings, forming a part thereof.

Fig. 1 is a front view of a medallion showing my new design.

Fig. 2 is a side view of the same.

It is understood that my design may be embodied in such articles as a medallion, medal, badge, plaque, or sign, without departing from the spirit of my invention.

The essential features of my design are shown in full lines.

I claim:

The ornamental design for a medallion or similar article, as shown and described.

THOMAS H. JONES.
